UNITED STATES PATENT OFFICE.

JAMES D. MAYBERRY, OF MINNEAPOLIS, MINNESOTA.

CONVERTIBLE CHAIR, IRONING BOARD, AND TABLE.

Application filed March 4, 1922. Serial No. 541,039.

To all whom it may concern:

Be it known that I, JAMES D. MAYBERRY, a citizen of the United States, residing at Minneapolis, in the county of Hennepin and 5 State of Minnesota, have invented certain new and useful Improvements in Convertible Chairs, Ironing Boards, and Tables; and I do hereby declare the following to be a full, clear, and exact description of the invention, such as will enable others skilled 10 in the art to which it appertains to make and use the same.

This invention relates to a combination article of furniture, and while the said article can be made of any desired size and form, 15 a regular article of furniture, it is more particularly designed to be made in small sizes and to be used as a device for children.

It is an object of the present invention to 20 provide a chair having the usual spaced back portions, the upper portions of which are hinged and adapted to fold forwardly and have secured thereto a table forming member.

It is another object of the invention to 25 provide a chair having a drawer formed under the seat thereof, the rear portion of which drawer is adapted to support an auxiliary back for the chair, which back is 30 adapted to be supported in one position to form an ironingboard.

It is another object of the invention to provide a bail pivoted in the spaced back portions of the chair, which bail may be used 35 in various positions to retain a child in the chair or to form a support for the auxiliary back member when used as an ironingboard.

These and other objects and advantages 40 of the invention will be fully set forth in the following description made in connection with the accompanying drawings in which like reference characters refer to the same parts throughout the different views, and in which—

Fig. 1 is a view in side elevation of the device showing a different position thereof in dotted lines;

Fig. 2 is a horizontal section taken on the line 2—2 of Fig. 1, as indicated by the ar-

rows, also showing a different position thereof in dotted lines; 50

Fig. 3 is a view in central vertical section showing one combination of the device;

Fig. 4 is a view in horizontal section taken on the line 4—4 of Fig. 3; and 55

Fig. 5 is a fragmentary section showing a modification of the device.

Referring to the drawings, a chair is shown having rigid legs 1 which are continued upwardly above the rigid seat portion 60

2 at the front and rear to form supports for rigid side arm portions 3. Cross members 5 and 6 extend between the members 1 at the rear and front, respectively, and said members 1 are also joined by rigid side portions 4. Cleat members are provided on the inner sides of the members 4 which, together 65

with the member 6, form the supports for a drawer 7 which is thus disposed immediately under the seat portion 2, which 70 drawer is provided with the usual operating knob at its front end. The upper portions of the rear members 1, it will be noted, form

spaced rigid back members, and members 8 are provided forming extensions of the 75 spaced back members which members 8 are pivoted to the upper rear part of the arms 3 by suitable hinges, as shown, so that the same can be swung downwardly and forwardly. The members 8 have rigidly secured thereto and extending between the 80

same, a central member 9, which member has hinged thereto at each side, the sections 10, which sections are adapted to be opened out and swung into alignment with the member 9, said member and sections being shaped 85

to constitute a circular table, as indicated in Fig. 2. While the member 9 can be secured to members 8 in any desired manner it is shown as having cleats 9^a secured thereto 90

which are received in recesses in the members 8 formed to fit and receive the same. As also shown in said figure the members 10 normally are folded back of the member 9. It will be noted that the members 9 and 95

10 will swing forwardly and downwardly with the members 8 and in order to hold said members as well as the members 8 in

position shown in Fig. 1, hooks 12 are provided on each of the rear members 1 to hook into eyelets screwed into the sides of member 9.

5 It will be noted that the seat member 2 is discontinued at the rear portion to expose the rear part of the drawer 7 and this part of the drawer forms a support for an auxiliary back member 11 adapted to extend 10 from the bottom of the drawer upwardly to substantially the top of the member 9. This member 11 is of a shape illustrated in Fig. 4.

15 A bail member 13 is provided of substantially rectangular shape with curved corners, the ends of which are out-turned and adapted to pivot in holes 8^a formed on the inner sides of members 8. As shown in Figs. 3 and 4, this bail member extends forwardly 20 from the members 8 and can be disposed in different positions. The member 11 is arranged to be used as an ironing board and for this purpose, a plurality of pairs of alined cleat members 14 are provided extending horizontally and secured at different points to each side of the member 9. When the member 11 is to be placed in position for an ironingboard, the same will be 25 lifted from the drawer 7, the straight end thereof inserted under one pair of the cleats 14 against the member 9 and the same extended horizontally over the bail member which is then secured in one of its upper positions. The cross member of the bail then 30 engages with a cross strip or cleat 15 screwed, or otherwise secured to the bottom of member 11.

35 In one position, which may be taken as the normal position, the chair will be arranged 40 as shown in Fig. 1 and will then simply constitute an ordinary chair having the usual seat, arms and back portions, the back portion being formed by the member 11. If it is now desired to form a table, the member 45 11 will be removed, the hooks 12 unhooked and the members 8, together with the members 9 and 10 swung forwardly. The members 8 will then, as shown in Fig. 1, rest on the arms 2 and the sections 10 will be opened 50 out. A flat top circular table is then formed having a smooth flat upper surface. This table will be substantially supported and 55 will form a convenient card table, dining table, or table for any other desired purpose. This table may, of course, be made of any other shape than circular by simply varying the shape of the members 9 and 10. If desired to use the member 11 as an ironingboard, the same will be disposed, as 60 shown in Fig. 3 and as already described. It will be noted that the drawer 7 forms a convenient place to keep children's toys when the device is used as a child's chair and this drawer will be normally held in closed 65 position by the member 11.

The bail member 13, when placed in its lower position, may be used as a holder to retain a small child in the chair.

70 In the modification shown in Fig. 5, the members 10 are pivoted or hinged to swing forwardly instead of rearwardly, as shown in Fig. 2. These members can be upholstered, together with the back portions and will then form side portions for the chair. Any desirable means may also be provided 75 to hold the same in the position shown in Fig. 5. It will also be understood that the various parts of the chair shown may be upholstered, as desired, to form a rich and comfortable piece of furniture.

80 From the above description it is seen that applicant has provided a very simple and very convenient article of furniture. The parts of the chair are few and can be made quite rugged.

85 It will, of course, be understood that various changes may be made in the form, details and arrangement of the parts without departing from the scope of applicant's invention, which, generally stated, consists in 90 the matter shown and described and set forth in the appended claims.

95 What is claimed is:

1. A combination article of furniture comprising a chair having rigid seat and leg portions, the rear leg portions being extended upwardly to form spaced back portions, rigid arms connected thereto, upper back portions forming continuations of said spaced back portions hinged to said arms, a panel secured to said upper back portions extending therebetween and having transverse members secured thereto, sections hinged to each side of said panel and adapted to swing into the plane thereof and form 100 a table therewith, said table and said hinged upper back portions adapted to swing forwardly and downwardly and be supported on said arms and a member adapted normally to be supported in front of said panel 110 to form an auxiliary back rest but being adapted to be supported in a horizontal position in front of said panel in contact with one of said transverse members to form an ironingboard.

115 2. A combination article of furniture comprising a chair having spaced back portions, a bail having its ends pivoted therein and extending forwardly, a member secured to said back portions and extending therebetween, spaced cleat members on said member and an auxiliary back member adapted to be supported in a horizontal position with its end under said cleats and extending over said bail and projecting forwardly from the member extending between said back portions.

120 3. A combination article of furniture comprising a chair having a rigid seat, legs and arms; a hinged upper back portion adapted 125

to form a table, a drawer under said seat and projecting to the rear thereof, an auxiliary back member supported at its lower end in said drawer and at its upper end by 5 said back member.

4. A chair having in combination, leg, and seat portions, a normally upright back portion comprising laterally movable hinged sections, means forming arms for support-

ing said back portion in horizontal position 10 to form a table, a normally upright auxiliary back portion, and means intermediate the top and bottom of the back portions for supporting the same in horizontal position to form an ironingboard.

15 In testimony whereof I affix my signature.

JAMES D. MAYBERRY.
